UNITED STATES PATENT OFFICE

2,607,379

SOFT METAL HAMMER

Frank Piampiano, Lake Hiawatha, and Arthur H. Bennett, Livingston, N. J., assignors, by direct and mesne assignments, to Last-Long Safety Hammer Co., Orange, N. J., a corporation of New Jersey

Application August 4, 1950, Serial No. 177,672

2 Claims. (Cl. 145—36)

1

This invention relates to improvements in hammers, and more particularly to an improved hammer head, the primary object of the invention being to provide a hammer head which eliminates or reduces damage to other metals hammered therewith and prevents production of sparks while hammering.

Another important object of the invention is to provide a more practical and more efficient metal working hammer head of the character indicated above composed of copper alloy and having cavities therein at opposite sides of and spaced from the handle receiving eye thereof and located in the opposite ends of the head, in which are positioned spring inserts which act to prevent spreading of the faces of the hammer in use which otherwise would occur due to the non-resilient character of copper.

Other important objects and advantages features of the invention will be apparent from the following description and the accompanying drawings, wherein, merely for purposes of illustration herein, a specific embodiment of the invention is set forth in detail.

In the drawings, wherein like numerals designate like parts throughout the several views:

Figure 1 is a top plan view,

Figure 2 is an end elevation,

Figure 3 is a longitudinal section taken on the line 3—3 of Figure 1, and

Figure 4 is a transverse section taken on the line 4—4 of Figure 3.

Referring in detail to the drawings, the illustrated hammer head is preferably composed of from 94% to 96% copper, 2% to 3½% silicon, and ½% of tin. The hammer head consists of a solid body 5 of copper alloy having a substantially square middle portion 6 through which extends the handle receiving eye 7 opening through the top and bottom surfaces 8 and 9 respectively, of the middle portion 6, and tapering from the top surface 8 to the bottom surface 9.

Extending at right angles to the eye 7 are centered and aligned bores 10 which open through the opposite sides 11 of the middle portion 6 and accommodate a preferably brass pin 12 to hold the handle (not shown) in place in the eye 7.

The hammer head body 5 has similar end portions 14 which are square in transverse cross section and tapered uniformly from the middle portion 6 to their outer ends 15. The outer ends 15 are plane and smooth and are positioned at right angles to the longitudinal axis of the body 5.

2

Each end portion 14 is hollow, being formed with a square cavity or chamber 16 which is centralized with respect to the sides and tops and bottoms of the end portions 14, but are closer to the eye 7 than to the outer ends 15 of the end portions, as indicated in Figures 3 and 4. The size and arrangement of the chambers 16 are such that the end portions 14 while hollow, are characterized by heavy, relatively rigid walls supporting the outer ends 15.

The longitudinally inward ends 17 of the chambers 16 are formed with access openings 18 communicating with the eye 7 through which a spring insert 19 is passed into each chamber.

The spring inserts 19 are similar, each being a flat ribbon steel form comprising a straight bight portion 20 from whose opposite ends extend legs 21 involving an inwardly angulated portion 21 terminating in an outwardly angulated portion 22, the portions 21 and 22 being the same in length. The spring inserts are adapted to be inserted into the chambers 16 by passing their bight portions 20 through the access openings 18 from the eye, followed by the legs in compressed position.

As the legs pass the access openings 18 they spring apart so that the terminal ends or edges 23 of the leg portions 22 engage the inner ends 17 of the chambers on opposite sides of the access openings 18, the length of the legs being such that the legs then press the bight portions 20 against the outer ends 24 of the chambers. As a result, the spring inserts 19 act as resilient supports backing up the outer ends 15 of the end portions 14 of the hammer head, which prevent undue flattening and spreading and other permanent distortion or deformation of the end portions 14 as a result of hammering upon other metal objects which would otherwise take place due to the plasticity of the copper material.

It is to be noted that the spring inserts 19 are positioned in the chambers 16 with their legs in the vertical plane of the hammer head body 5, which is coincident with a plane passing through the eye 7 and hence through an associated handle (not shown), the spring inserts 19 thereby being arranged to resist such distortions of the head ends as naturally occur in the swinging of the hammer head in a general plane passing through the handle and the longitudinal axis of the hammer head, as one of the ends 15 strikes the work at an angle or otherwise than flush with the work.

The relative softness and yielding character of a hammer head constructed as above de-

scribed and formed of copper cushions its engagement with other objects struck thereby, so as to avoid damage to such objects. The copper alloy prevents generation of sparks such as is incidental to striking a ferrous object with an iron or steel hammer.

What is claimed is:

1. In a hammer head, a copper body having an end terminating in a striking face, said end being normally subject to inward distortion when said striking face is hammered against a resistant object, a chamber formed in said end in spaced relation to the sides of said end and to said striking surface, and a spring insert confined in said chamber under tension and serving to resiliently resist inward distortion of said end, said striking surface and one end of said chamber defining an end wall therebetween, said spring insert comprising a bight portion engaging said end wall and legs extending from said bight portion and bearing against an opposite end of said chamber.

2. In a hammer head, a copper body having an end terminating in a striking face, said end being normally subject to inward distortion when said striking face is hammered against a

resistant object, a chamber formed in said end in spaced relation to the sides of said end and to said striking surface, and a spring insert confined in said chamber under tension and serving to resiliently resist inward distortion of said end, said striking surface and one end of said chamber defining an end wall therebetween, said spring insert comprising a bight portion engaging said end wall and legs extending from said bight portion and bearing against an opposite end of said chamber, said body having a handle accommodating eye and being formed with an access opening extending between said eye and said chamber through which said spring insert is adapted to be inserted into said chamber.
